UNITED STATES PATENT OFFICE

CARL D. BUNKER, OF NORTH HAVEN, MAINE

DESIGN FOR A SMOKER'S STAND

Application filed April 21, 1932. Serial No. 48,563. Term of patent 7 years.

To all whom it may concern:

Be it known that I, CARL D. BUNKER, a citizen of the United States, residing at North Haven, in the county of Knox and State of Maine, have invented a new, original, and ornamental Design for a Smoker's Stand, of which the following is a specification, reference being had to the accompanying drawing, forming part thereof.

The figure is a view in perspective of a smoker's stand, showing my new design.

I claim:

The ornamental design for a smoker's stand, as shown.

CARL D. BUNKER.
